HOSIERY INSPECTING DEVICE

Max Poeschmann, West Reading, Pa., assignor
to Textile Machine Works, Wyomissing, Pa., a
corporation of Pennsylvania

Application July 17, 1936, Serial No. 91,107

15 Claims. (Cl. 223—77)

This invention relates to hosiery inspecting devices of that type disclosed in U. S. Letters Patent to Samuel E. Kalbach and Max Poeschmann, which bears No. 2,092,806, and which was issued by the United States Patent Office on September 14, 1937.

In devices of the type noted a hollow substantially closed, circular, and gradually tapering shell constitutes a pole-like hosiery form. The form is adapted to be placed within a stocking or to have a stocking drawn over it, longitudinally thereof. The hosiery form, with a stocking thereon, is adapted to be expanded laterally or radially, to place the fabric of the leg, foot and heel portions of the stocking under tension. The radial movements of the leg, foot and heel tensioning members of the inspection form are effected by a single longitudinally reciprocable element extending axially through the form.

In devices of the type above noted, as disclosed in the above-mentioned patent, the centrally located operating element is arranged to be actuated solely by a foot treadle or through pneumatically or hydraulically actuated means controlled by the foot treadle. The motivating means is arranged externally of, and remotely with respect to, the form and is connected to the form actuating element through a series of links, gears, racks, etc.

The present invention relates principally to an improved means for operating the centrally located actuating element of the form; and to various details of the structure, and an object of the present invention is to provide for simplicity of construction and operation of the device.

With this and other objects in view, which will become apparent from the following detailed description of the illustrative embodiment of the invention shown in the accompanying drawings, my invention resides in the novel structure and method of operation as hereinafter more particularly pointed out in the claims.

The structure forming the subject matter of the present invention, and its application to an inspection form of the type noted, will be fully disclosed hereinafter, reference being had to the accompanying drawings; of which:

Figure 1 is a front elevation of the inspecting form and, in the present instance, a table to which the form is secured for operation;

Fig. 2 is a plan view of the inspecting form and its associated mechanism and illustrates the table in broken line and the form in a position 90° from that in which it appears in Fig. 1;

Fig. 3 is a transverse sectional elevation taken on the line 3—3, Fig. 2;

Fig. 4 is a transverse sectional elevation taken on the line 4—4, Fig. 2;

Fig. 5 is a side elevation of the form per se with the heel expander shown in its effective position;

Fig. 6 is a longitudinal sectional elevation of the form as taken on the line 6—6, Fig. 2;

Fig. 7 is a sectional plan view of the form as taken on the line 7—7, Fig. 6, with the form in its expanded condition;

Fig. 8 is an enlarged detail view of the heel expander in its effective position;

Fig. 9 is a view similar to Fig. 8 showing the heel expander in its ineffective position;

Fig. 10 is a sectional plan view taken on the line 10—10, Fig. 9;

Fig. 11 is a transverse sectional elevation taken on the line 11—11, Fig. 9;

Fig. 12 is a transverse sectional elevation taken on the line 12—12, Fig. 9;

Fig. 13 is an enlarged sectional elevation of the actuating motor for the form expanding element, the section being taken on the line 13—13, Fig. 4;

Fig. 14 is a fragmentary sectional elevation as taken on the line 14—14, Fig. 3;

Fig. 15 is a transverse sectional elevation taken substantially on the line 15—15, Fig. 14;

Fig. 16 is a sectional elevation of a detail of the invention as taken on the line 16—16, Fig. 4; and

Fig. 17 illustrates a detail of the invention substantially as appearing on the line 17—17, Fig. 3.

As shown principally in Figs. 6 and 7, the device comprises a form-supporting head 1 which is adapted to be firmly secured to any suitable rigid support. Projecting axially from one end of, and rigidly secured in or to the head 1, is a short fixed stud or post 2. In the present instance, the fixed post 2 carries ball bearings 3 and 4. The ball bearings 3 and 4 are spaced apart axially along the post 2 beyond the head 1. The ball bearings 3 and 4 are mounted within a relatively long center post 5, adjacent to one end thereof, and by which the post 5 is adapted to be freely rotated about the axis of the fixed post 2.

The rotatable post 5 constitutes a foundation structure for the inspection form 6. The form 6 is composed of a plurality of longitudinally extending radially movable segments which collectively form a hollow shell which surrounds the foundation post 5 and tapers externally from a relatively large diameter adjacent to the head 1 to a relatively smaller diameter at that end of

the shell which is remotely situated with respect to the head 1.

The shell 6 constitutes the leg-expanding section of the form and, in the present instance, is composed of two segmental sections 6a and 6b, respectively, which are of similar construction and mounted on the foundation post 5 for movement in opposite, lateral or transverse directions with respect to each other or radially with respect to the axis of the foundation post 5.

Axially aligned with the tapering leg portion of the expansible shell 6, and extending beyond the outer end 7 thereof, is the foot expanding section 8. The foot expander 8, like the leg expander 6, is composed of a pair of similar sections 8a and 8b. The foot expander sections 8a and 8b are respectively secured to the leg expander sections 6a and 6b, said sections being secured together in such a manner as to provide for axial adjustment between the foot expander and the leg expander, as fully disclosed in said copending application.

The inner end 9 of the foot expanding section 8 of the form is movable away from the outer end 7 of the leg expanding section 6 of the form for the reception of filler pieces 10, which are adapted to close a gap between the foot and leg portions which would otherwise occur as a result of longitudinal adjustment of the foot section 30 with respect to the leg section.

The two segments 6a and 6b of the leg-expanding shell 6 are supported for relative lateral or radial movement on, and with respect to, the foundation post 5 by a pair of plate-like lugs 11a and 11b, respectively; and by a pair of transversely extending and movable rods 13a and 13b, respectively, said rods being slidably mounted in cylindrical bearings 15, 15 formed in, or carried by, the post 5, the plates 11a and 11b being arranged in overlapping relation one to the other and mounted within a transversely extending slot, recess, or slideway 12 formed in the foundation post 5.

Simultaneous movement of the leg expander sections 6a and 6b, with the foot expander sections 8a and 8b respectively secured thereto, is effected by means of a centrally disposed longitudinally reciprocable actuating element 20. The actuator 20 is slidably mounted in the post 5 and is adapted for axial movement with respect thereto.

The plates 11a and 11b are provided with acute angle slots 21a and 21b, respectively, in which is mounted a common operating pin 22, said pin being fixed to the actuating element 20 for movement therewith.

The supporting rods 13a and 13b are respectively provided with pins 24 and 25 which project through transversely extending slots 26 formed in the cylindrical bearings 15 for said rods and into angularly disposed slots or grooves 27 and 28 formed in one or both of the opposite side walls of a longitudinally extending recess or slot 18a formed in an enlarged portion 18 of the actuating element 20.

The actuating element 20, see Fig. 13, is provided with or includes an axial extension 19 which passes axially through the center bore of the supporting post 2 for connection with an actuating motor M, as will be fully disclosed hereinafter.

The form is also provided with a heel expander 30, see Figs. 8 and 9, which is pivoted at 31 to a suitable lug 41 formed on the extreme end of the foundation post 5 within the leg expander 6,

said heel expander being adapted to swing outwardly or radially with respect to the axis of the post 5 through a suitable opening 32 formed half in the shell section 6a and half in the shell section 6b. 5

Radial movement of the heel expander 30 is effected by means of a pin 33 carried by and projecting laterally from both sides of a block 34, which is formed on or secured to the outer end of the centrally located actuating element 20, 10 beyond a bearing 35 provided at the outer end of the post 5 and in which the outer end of the actuator 20 is slidably mounted.

The opposite ends, respectively, of the pin 33 are disposed in angularly arranged cam slots 36, 15 36 which are, respectively, formed in movement determining members or swing adjusting plates 37, 37. The swing adjusting plates 37, 37 are located at the opposite sides, respectively, of a central rib 38 on the heel expander 30, and are 20 connected to the rib 38 through means of fixed side plates 39, 39 which are secured to said rib by screws 40, 40.

The side plates 39, 39 pass to opposite sides, respectively, of the lug 41 which carries the pivot 25 pin 31 for the foot expander 30 and constitute the bearings for the pivot pin 31 in the heel expander.

The plates 37, 37 are mounted on the plates 39, 39 for adjustment with respect thereto, for the 30 purpose of adjusting or controlling the extent of the outward movement of the heel expander 30, for stockings having different length feet and for this purpose each plate 37 at one end 42 of the cam slot 36 therein is provided with a circular 35 boss 43 which is mounted in a circular bearing opening 44 formed in the adjacently disposed side plate 39, whereby the plates 37 may be swung about the axes of the bosses 43 with respect to the side plates 39 to increase the angles of the 40 cam slots 36 with respect to the line of movement of the actuating pin 33 and the central actuator 20. This structure is clearly illustrated in Figs. 10, 11 and 12.

The plates 37 are adapted to be secured in the 45 positions to which they are adjusted by means of clamp screws 45 which pass through arcuate slots 46 swung from the axes of the circular bosses 43, said screws being threaded into tapped openings in the adjacently disposed side plates 39, 39 respectively.

From the above description, it will be obvious that longitudinal reciprocation of the central actuating element 20, which in the present instance is effected by the actuating motor M, will cause 55 radial expansion and contraction of the sections 6a and 6b of the leg expanding shell 6, with respect to the center foundation post 5, carrying with them the foot expander sections 8a and 8b respectively and simultaneously therewith the 60 heel expander 30 will be swung radially outwardly and inwardly with respect to the leg and foot sections of the inspecting form.

It will be obvious that the fabric of a stocking which has been placed on the form, as indicated at S in Fig. 5, will be subjected to lateral tension throughout the length of the leg, foot and instep portions S¹, S² and S³ respectively of the stocking; and that with the toe portion S⁴ of the stocking drawn firmly against the outer 70 or toe-engaging end of the foot expander 8, the heel expander 30, in swinging about its pivot 31, will cause the outer or free end of said expander to engage the heel S⁵ of the stocking and as said heel-engaging end of the heel expander 75

swings radially it also moves upwardly at an angle with respect to and away from the toe-engaging end of the foot expander 8, and in so doing places the foot sole section S⁶ of the stocking S under longitudinal tension at the same time as lateral tension is applied to the whole of the stocking fabric.

In the present instance, the actuating motor M comprises a form-supporting head 1 which is of hollow cylindrical construction and is closed at its opposite ends by head plates 50 and 51 respectively. The head plate 50 is provided with a central circular boss 52 (Fig. 13) which extends inwardly and axially of the hollow cylinder 10 head 1 and affords rigid support for the hollow form-supporting stud or post 2.

The opposite end of the form-supporting head 1 is bored and finished to provide a cylinder 53 in which is slidably mounted a piston 54, said piston being of the hollow type open at one end and provided at its opposite end with a head 55. When the stocking form is in its collapsed or closed condition the piston head 55 lies immediately adjacent to the inner surface of the cylinder head 51, to provide, between the cylinder head 51 and the piston head 55 a motive fluid cavity 56.

Formed on the piston head 55 and extending axially of and within the piston 54 is a circular boss 57, between the outer peripheral surface of which and the inner surface of the cylindrical wall 58 of the piston 54 is provided an annular cavity 59.

The annular cavity 59 is arranged to receive one end of a spring 60 which encircles the central boss 57 with its extreme end abutting against the inner surface of the piston head 55, the opposite end of said spring being seated against an annular shoulder 61 formed on the inner end 40 of the cylindrical boss 52 of the closure plate 50 of the form-supporting head 1. The spring 60 at all times tends to move the piston 54 in a direction toward the cylinder head 51 to maintain the inspection form in its contracted or closed condition.

In order to effect operation of the form expanding and contracting element 20, the end 19 of the central actuator 20 is connected to the piston 54 of the motor M in a manner to insure coordinate reciprocation of the actuator 20 with the piston 54 and for that purpose the extended portion 19 of the actuator 20 is enlarged in diameter inwardly from its extreme end and this enlargement 19a is externally threaded, for purposes hereinafter described. From one end of the screw threaded enlargement 19a to the extreme end of the extension 19 the actuator 20 is reduced in diameter as indicated at 19b. The reduced portion 19b of the actuator 20 projects 50 into a circular bore 62 formed in the hollow circular boss 57 of the piston 54. Surrounding the reduced end 19b, within the bore 62, are ball bearings 63 and 64, by which the actuator 20 is rotatably mounted in the piston 54.

In order to effect simultaneous axial movement of the piston 54 and actuator 20 upon operation of the actuating motor M the outer ball race of the bearing 63 is confined within the bore 62 of the piston 54, by means of a ring 65 which is secured to the piston boss 57 by screws 66. The inner edge of the ring 65 overhangs the bore 62 and forms an abutment for the outer race of the ball bearing 63. The inner race of the ball bearing 63 is seated directly on the extension 19b of the actuator 20 and is spaced from

the one end of the threaded enlargement 19a by means of a sleeve 67. The opposite side of the inner race of the ball bearing 63 is engaged by one end of a sleeve 68. The sleeve 68 is secured in any suitable manner to the extension 19b of the actuator 20 and thereby said actuator is prevented from being withdrawn from said sleeve, in order that reciprocation of the piston 54 will effect corresponding reciprocation of the actuator 20. The sleeve 68 is shouldered adjacent to its outer end for the reception of one race ring 69 of the ball bearing 64 which ball bearing functions as an end thrust bearing for the actuator 20. The second race ring 70 of the ball thrust bearing 64 is engaged by a plug 71 which is threaded into the tapped end 72 of the bore 62. The plug 71 is provided with an axial circular extension 73 about which the ball race 70 is seated.

The plug 71 is split transversely, as indicated at 74, and a locking screw 75 is employed to effect binding of the plug in the threaded bore 72 to prevent loosening thereof. A second flanged plug 76 is threaded into the extreme end of the threaded bore 72 and closes said bore and provides a substantially flat surface on the piston head 55, or the plug 76 may project beyond the face of the piston head 55 for engagement with the cylinder head 51 to insure provision of the fluid space 56.

From the above, it will be noted that reciprocation of the piston 54, as effected upon operation of the motor M, will effect reciprocation of the actuator 20 while permitting said actuator to revolve freely with respect to the piston. Such turning of the actuator 20 with respect to the piston is provided for in order to effect adjustment of the device to control the extent to which the stocking form or post 6 may be expanded laterally or radially.

As will be observed upon referring to Fig. 7, the distance the pins 22, 24 and 26 move in the cam slots 21a, 21b, 27 and 28 determines the extent to which the form sections 6a-8a and 6b-8b can be separated. Consequently the extent of expansion of the form is controlled by the extent of axial movement of the actuator 20.

As noted above, the spring 60 moves the actuator 20 in one direction to collapse or contract the form 6 fully, and the piston 54, operated under fluid pressure entering the space 56 between the head 55 of said piston and the head 51 of the cylinder and which moves the piston in opposition to the spring 60, expands the form. Consequently, by controlling the extent of movement of the piston the extent of expansion of the form is controlled.

The extent of movement of the piston in the direction to expand the form is controlled in the following manner: Threaded onto the screw threaded enlargement 19a of the actuator is a sleeve 80. Mounted on the end of the sleeve 80 nearest the piston 54, between the inner end 81 of the circular boss 52 of the head plate 50 and the ring 65 which is secured to the inner end of the circular boss 57 of the piston 54, is a ball bearing 82 which is fixed to the sleeve 80 against relative axial movement therebetween. The inner end of the boss 52 is shouldered as indicated at 83 for the reception of an abutment ring 84 which may be composed of any resilient material such, for example, as felt. This abutment ring is adapted to be engaged by the outer race ring of the ball bearing 82 which functions as a stop to limit the movement of the piston 54 and consequently the actuator 20 when moving in the

form-expanding direction. By varying the relation between the stop 82 and the piston 54, in a direction axially of the actuator 20, the extent of expanding or expansion of the form 6 is correspondingly controlled. Such variation is effected by producing relative rotation between the sleeve 80 and the threaded enlargement 19a of the actuator 20.

The actuator 20 is provided with a resilient key 85 (see Fig. 14) which, in the present instance, consists of a flat spring 86. The spring 86 is mounted in a longitudinal groove 87 formed in the actuator 20 and is secured at one end to said actuator by a screw 88. The opposite end of the flat spring 86 is provided with a projection 89 which normally rests in a longitudinal slot 90 formed in the sleeve 80 and normally prevents relative rotation between the sleeve 80 and the actuator 20.

In order to adjust the sleeve 80 with respect to the actuator 20, the key 85 is moved laterally of the actuator 20 to release the actuator 20 from said sleeve 80. This is accomplished by a plunger 91, see Figs. 14 and 15. The plunger 91 is slidably mounted in a thimble 92 which is secured in an opening 93 formed in the head 1 and projects through an opening 94 formed in the boss 52, with the inner end of the plunger 91 passing through an opening 95 formed in the post or stud 2. The outer end of the plunger 91 is provided with a head 96. A spring 97, encircling the plunger 91 in the bore of the thimble 92 between the base of said bore and the inner end of the head 96, tends to move the plunger 91 at all times to an inoperative position. A pin 98 carried by the plunger 91 and bearing against the inner end of the thimble 92 prevents said plunger from being ejected from the thimble by the spring 97.

In order to effect relative adjustment between the sleeve 80 and actuator 20, the stocking form is rotated until the slot 90 of the sleeve 80 is in alignment with the plunger 91. The plunger is then pressed inwardly until the inner end thereof engages the lug 89 of the key 85 and until said lug is removed from the slot 90 of the sleeve 80, at which time the plunger 91 locks the sleeve 80 against rotation but at which time the actuator 20 may be rotated with respect to the sleeve 80. Such rotation of the actuator 20 is effected by rotating the whole of the form about its axis which causes the threaded enlargement 19a thereof, by reason of its threaded engagement with the then fixed sleeve 80, to move longitudinally of and within said sleeve, moving the piston 54 correspondingly and thereby changing the relationship between said piston and the stop 84 and in so doing the allowable amount of travel of the pins 22, 24 and 25 relative to the slots 21a, 21b, 27 and 28 is determined which in turn determines the extent of lateral and radial expansion of the two oppositely arranged half sections of the form.

In addition to the controlling of the extent of expansion of the form as a whole, the extent of relative expansion movement between the body of the form and the heel expander is accomplished in the manner noted above, i. e. by adjusting the plates 37 and 39 of the heel expander 30 relative to each other as noted.

The control of the fluid pressure entering the fluid space 56 in the head of the motor M and the exhaust of said fluid from said space or from that end of the cylinder 53 between the piston

head 55 and cylinder head 51 is effected, in the present instance, by means of a slide valve 100.

In the present instance, see Fig. 4, the slide valve 100 is mounted for reciprocation in a bore 101 of a valve chest 102. The valve chest 102 is secured to the head 1 by means of bolts 103. The wall of the valve chest 102 is provided with a pair of ports 104 and 105 respectively. The port 104 connects with one end of a fluid passage 106 formed in the head 1, the opposite end of said fluid passage communicating with the fluid space 56 formed between the piston head 55 and cylinder head 51. The port 105 connects with one end of a fluid passage 107 formed in the head 1. The opposite end of the passage 107 communicates with a port 108 formed in a hollow bracket 110 to which the head 1 is secured in any suitable manner. The hollow interior of the bracket 110 is provided with overlapping baffles 109 which form a circuitous path through which fluid passing from the passage 107 must flow in order to escape from the hollow interior of the bracket 110 through a suitably screened outlet orifice 111. The screen for the outlet 111 in the present instance is in the form of perforated plate 112, which is removably secured to the bracket 110 as by screws 113.

The slide valve 100 is provided with a longitudinally extending recess 114 formed in its peripheral surface and which, when in the position shown in Fig. 4, affords communication between the ports 104 and 105 through the bore 101 of the valve chest 102 and provides for the exhaust of motive fluid from the end of the cylinder 53 intermediate the piston head 55 and cylinder head 51.

The velocity of the exhausting fluid is reduced by the circuitous path the fluid is required to follow in passing around the baffles 109 and the pressure of the exhausting fluid is reduced by reason of its passing into the large cavity of the bracket 110 which functions as an expansion chamber for the exhaust fluid coming from the cylinder 53.

Live motive fluid is conducted to the valve chest 102 of the motor by means of a fluid pipe 115 connecting the valve chest with any suitable source of fluid supply. In the present instance, the device is arranged to be actuated by compressed air, although obviously steam or other gaseous fluid under pressure may be employed.

The feed pipe 115 is connected to a port 116 in the valve chamber 102 which in turn communicates with the bore 101 of said valve chest. The valve 100 is provided with a longitudinally extending recess 117 in its peripheral surface and which communicates with the port 116 at all times. The valve 100 is provided with a transversely extending passage 118. One end of the passage 118 communicates with the recess 117 while the opposite end of the passage 118 is arranged in longitudinal alignment with the longitudinal recess 114 in said valve, whereby movement of the valve 100 axially to the right as viewed in Fig. 4 will effect an interruption of the communication between the ports 104 and 105, through the recess 114 in the valve 100, and which will form communication between the transverse passage 118 of the valve 100 and the port 104 of the valve chest 102, permitting motive fluid to flow from the pipe 115 through the port 116, recess 117, passage 118, port 104, and passage 106 to the fluid space 56 in the cylinder 53, which will move the piston 54 in a direction to effect expansion of the stocking form until the

stop 82 engages the fixed stop ring 84, which determines the extent of expansion of said form.

The above noted movement of the piston 54 places the spring 60 under compression. Reverse movement of the valve 100 first cuts off the flow of motive fluid from the pipe 115 and reestablishes communication between the ports 104 and 105 through the recess 114 in the valve 100, whereupon reaction of the spring 60 moves the piston 54 in the opposite direction and exhausts the spent fluid from the cylinder 53 in the manner above noted.

Reciprocation of the valve 100 is provided for in the following manner: The valve 100 is provided with a valve stem 120 which passes out of the valve chest 102 through a suitable stuffing box 119. The stem 120 is connected at its outer end, at 121, to an adjustable link 122, said link being connected at its opposite end, at 123, to a lever 124. The lever 124 is secured to a shaft 125. The shaft 125 is rotatably mounted in bearings 126, 126 which are secured to the under side of a work table 127 as indicated in Figs. 1, 2 and 3. Secured to the shaft 125 is a pair of depending arms 128, 128. Carried by the lower ends of the arms 128 is a foot treadle 129.

The shaft 125 is at all times urged to turn in a direction to move the valve 100 to the position shown in Fig. 4, wherein exhaust of the motive fluid from the motor 53 is effected, by a spring 130, see Figs. 2 and 17. The spring 130 encircles the shaft 125 and has one of its ends secured to one of the shaft bearings 126. The opposite end of the spring 130 is anchored in a collar 131 which is adjustably secured to the shaft 125 by means of a set screw 132.

The link 122 comprises a pair of end pieces 133 and 134 which are axially threaded to receive right hand and left hand threads respectively 40 which are formed on the opposite ends of an adjusting bolt 135, which forms the intermediate member of the link. The adjusting bolt 135 is provided with a centrally located hexagonal or other flat side enlargement 136 by which rotation of the adjusting screw 135 is effected. Lock nuts 137, 137 threaded onto the opposite ends of the adjusting bolt 135 and arranged to be jammed down tightly against the ends of the members 133 and 134 lock the whole of the link 50 together as a single unit.

The end member 134 is bored inwardly from one end as indicated at 138 and slotted or otherwise apertured as indicated at 139, in Fig. 16, to receive a ball 140 which constitutes the pivot 55 123 between the one end of the link 122 and the arm 124, said ball being retained in the bore 138 by a plug 141 which in turn is secured in the link member 134 by a pin 142. The ball 140 is formed on one end of a bolt 143, beyond the head 60 144 thereof. The shank 145 of said bolt passes through a slot 146 formed in the lever 124, said bolt being secured in its adjusted position within said slot by means of a clamp nut 147 threaded on to the shank 145 of the bolt and between which 65 and the head 144 the lever 124 is clamped.

The form-head supporting bracket 110 is secured to the under side of the work table 127 and is provided with a step 150 in which the screened fluid exhaust port 111 is formed. As shown in 70 Fig. 3, the step 150 is substantially parallel to and spaced from the under side of the table 127 and provides an air space 151 between the under side of the table and the upper side of the screen 112, whereby exhaust fluid passing out through the screened opening 111 impinges upon the under

side of the table 127 and is dissipated in all directions, thus preventing the formation of air currents which normally would effect displacement of stockings or other work piled on the work table 127.

Of course, the improvements specifically shown and described, by which I obtain the above results, can be changed and modified in various ways without departing from the invention herein disclosed and hereinafter claimed.

I claim:

1. A hosiery inspecting device comprising a head, an elongated expandable hosiery form carried by said head and having rotative movement about its longitudinal axis relative to said head, means for expanding and contracting said form including an axially reciprocable element extending longitudinally of said form and into said head, a cylinder in said head, a piston operable in said cylinder and connected to said element for moving said element in one direction to expand said form, a spring for moving said element in the opposite direction to contract said form, a valve controlling the flow of motive fluid to and from said end of said cylinder for controlling the operation of said form, a pair of co-operating stops within said head and carried by said head and said element respectively for limiting the form expanding movement of said element, means for varying the relation between said stops to regulate the extent of expanding movement of said element, and means operative between positions in one of which said rotative movement causes said regulating means to vary said relation between said stops, and in another of which 30 said rotative movement is ineffective to cause said regulating means to vary said relation between said stops.

2. A hosiery inspecting device comprising a head, an elongated expandable hosiery form carried by said head and having rotative movement about its longitudinal axis relative to said head, means for expanding and contracting said form including an axially reciprocable element extending longitudinally of said form and into said head, a cylinder in said head, a piston operable in said cylinder and connected to said element for moving said element in one direction to expand said form, a spring for moving said element in the opposite direction to contract said form, a valve controlling the flow of motive fluid to and from said end of said cylinder for controlling the operation of said form, a stop adjustably mounted on said element, a fixed stop in said head for cooperation with said adjustable stop to 40 govern the extent of form expanding movement of each element, and means operative between positions in one of which said rotative movement actuates said adjustable stop, and in another of which said rotative movement is ineffective to 45 cause said adjustable stop to actuate said adjustable stop.

3. A hosiery inspecting device comprising a head, an expandable hosiery form carried by said head, means for expanding and contracting said form including an axially reciprocable element 65 extending longitudinally of said form and into said head, a cylinder in said head, a piston operable in said cylinder and connected to said element for moving said element in one direction to expand said form, a spring for moving said element in the opposite direction to contract said form, a valve controlling the flow of motive fluid to and from said end of said cylinder for controlling the operation of said form, a sleeve threaded onto said element, a stop carried by said 70 75

sleeve, and a cooperating stop on the inside of said head to govern the extent of form expanding movement of said element.

4. A hosiery inspecting device comprising a head, an expansible hosiery form carried by said head, means for expanding and contracting said form including an axially reciprocable element extending longitudinally of said form and into said head, a cylinder in said head, a piston operable in said cylinder and connected to said element for moving said element in one direction to expand said form, a spring for moving said element in the opposite direction to contract said form, a valve controlling the flow of motive fluid to and from said end of said cylinder for controlling the operation of said form, a sleeve threaded onto said element, a stop carried by said sleeve, a cooperating stop on the inside of said head to govern the extent of form expanding movement of said element, a key locking said sleeve against rotation on and relative to said element, and means extending externally of the head for releasing said key.

5. A hosiery inspecting device comprising a head, an expansible hosiery form carried by said head, means for expanding and contracting said form including an axially reciprocable element extending longitudinally of said form and into said head, a cylinder in said head, a piston operable in said cylinder and connected to said element for moving said element in one direction to expand said form, a spring for moving said element in the opposite direction to contract said form, a valve controlling the flow of motive fluid to and from said end of said cylinder for controlling the operation of said form, a sleeve threaded onto said element, a stop carried by said sleeve, a cooperating stop on the inside of said head to govern the extent of form expanding movement of said element, a key locking said sleeve against rotation on and relative to said element, and means for locking said sleeve against rotation in said head to provide for relative rotation between said element and said sleeve.

6. A hosiery inspecting device comprising a work table, a bracket secured to the underside of said table, a head secured to said bracket, a laterally expansible elongated stocking form carried by said head and having rotative movement about its longitudinal axis relative to said head, a cylinder in said head, a piston operable in said cylinder for expanding said form, variable means for regulating the extent of form expanding movement of said piston, means operative between positions in one of which said rotative movement causes said regulating means to vary the extent of said form expanding movement of said piston and in another of which said rotative movement is ineffective to cause said regulating means to vary the extent of said form expanding movement of said piston, a pair of plates respectively closing the opposite ends of said head, a stud carried by one of said closure plates for rotatably supporting said form, a spring acting between said stud carrying plate and one end of said piston for contracting said form, a valve chest secured to said head, and a valve operable in said chest for controlling the flow of motive fluid to and from a space between the opposite end of said piston and the second of said plates.

7. A hosiery inspecting device comprising an expansible stocking form including a central foundation element, a plurality of segmental members collectively forming a stocking form

around said foundation element, a heel member pivoted to said foundation element and arranged to swing radially outwardly therefrom between an adjacently disposed pair of said segmental members, a common actuator for all of said members, and means for effecting radial movements of one of said members of different extents relative to the radial movements of another of said members in response to like movements of said common actuator.

8. A hosiery inspecting device comprising an expansible stocking form including a central foundation element, a plurality of segmental members collectively forming a stocking form around said foundation element, a heel member pivoted to said foundation element and arranged to swing radially outwardly therefrom between an adjacently disposed pair of said segmental members, an inclined cam surface on each of said members, a common actuator for all of said members, means on said common actuator engaging with said inclined cam surfaces respectively, and means for varying the angle of the inclined cam surface of the heel member relative to the line of movement of the cam engaging means of the common actuator for regulating the extent of radial movement of the heel member for a given movement of the common actuator.

9. A hosiery inspection device comprising an extensible hosiery form, means for expanding and contracting the form including an element therein reciprocable longitudinally thereof, a sleeve threadably mounted on the reciprocable element, a stop on the sleeve, a cooperating stop to limit the form-expanding movement of the reciprocable element, and means for locking the sleeve against, and releasing it for, rotation relative to the reciprocable element.

10. A hosiery inspection device comprising a head, an extensible hosiery form supported by the head, means for expanding and contracting the form including an element therein reciprocable longitudinally thereof, a sleeve threadably mounted on the reciprocable element, a stop on the sleeve, a cooperating stop to limit the form-expanding movement of the reciprocable element, and means including an operating member associated with the head for locking the sleeve against, and releasing it for, rotation relative to the reciprocable element.

11. A hosiery inspection device comprising a head, an extensible hosiery form supported by the head, means for expanding and contracting the form including an element movably mounted in the form, a stop adjustably mounted on said element, a cooperating stop to limit the form-expanding movement of said element, and means operative between positions in one of which said rotative movement causes adjusting movement of one stop relative to the other, and in another of which said rotative movement is ineffective to cause adjusting movement of one stop relative to the other.

12. A hosiery inspection device comprising a head, an extensible hosiery form supported by the head, means for expanding and contracting the form including an element movably mounted in the form, a stop adjustably mounted on said element, a cooperating stop to limit the form-expanding movement of said element, and means including an operating member associated with the head providing for adjustment of the distance between said stops.

13. A hosiery inspection device comprising an

expansile leg form, means including an element longitudinally reciprocable in the form for expanding and contracting the form radially, a heel expander pivotally mounted in the form including a movement determining member normally fixed to the heel expander having a slot which in the contracted position of the heel expander is diagonal to said longitudinally reciprocable element, a pin on the latter element movable in said slot for moving the heel expander about its pivot, and means for adjusting the slotted member relative to the heel expander whereby the heel expander may move through any one of a selection of angles in response to a given stroke of the longitudinally movable element.

14. A hosiery inspection device comprising a stationary head, a longitudinally divided elongated stocking form supported at one end by said head and having rotative movement about its longitudinal axis relative to said head, means for expanding said form including an elongated element extending longitudinally of the form between said longitudinal divisions for moving said divisions laterally relative to each other, means supported by said head for actuating said elongated element, means operating between said elongated element and said actuating means for regulating the extent of said expansion, and means operative between positions in one of

which said rotative movement causes said regulating means to vary the extent of said expansion, and in another of which said rotative movement is ineffective to cause said regulating means to vary the extent of said expansion.

15. A hosiery inspection device comprising a head, a hosiery form supported by the head in movable relation thereto and including members movable relative to each other for expanding and contracting the form, said movement of the form relative to the head being utilizable as a hosiery inspection movement, relatively adjustable elements mounted in said head for effecting adjustment of the expanding and contracting movements of said members, means whereby said movement of the form relative to the head may also be effected to adjust said elements of the head relative to each other to effect adjustment of the expanding and contracting movements of said members, means for locking said elements of the head relative to each other whereby said movement of the form relative to the head is the said inspecting movement of an article of hosiery on the form, and means including an element for operating said locking means to release said elements from each other whereby said movement of the form relative to the head effects said adjustment.

MAX POESCHMANN.
